[57] CLAIM

The ornamental design for a computer keyboard lap pillow, as shown and described.

DESCRIPTION

FIG. 1 is a top plan view of a computer keyboard lap pillow showing my new design;

FIG. 2 is a bottom plan view thereof;

FIG. 3 is a left side elevational view, the right side being a mirror image thereof;

FIG. 4 is a left side elevational view of a second embodiment of the computer keyboard lap pillow shown in FIG. 1; the right side being a mirror image thereof;

FIG. 5 is a top plan view thereof;

FIG. 6 is a bottom plan view thereof;

FIG. 7 is a rear elevational view thereof;

FIG. 8 is a front elevational view thereof;

FIG. 9 is a front elevational view of FIG. 1; and,

10 is a rear elevational view of FIG. 1.
